SEWING MACHINE

Ralph E. Meredith and Joyce H. Meredith
Milwaukee, Wis.

Application July 29, 1939, Serial No. 287,296

9 Claims. (Cl. 112—104)

Our invention relates to improvements in sewing machines.

The object of this invention is to provide a sewing machine especially usable for sewing one piece of material to another, for instance, the sewing of a label upon the material of a garment or where the line of stitching produced by the sewing machine is automatically directed upon a predetermined path and means are provided for applying pressure upon the zone of the material within that path and for automatically removing the presser device.

More particularly stated, it is the object of this invention to provide a sewing machine or sewing machine attachment and equipment for sewing one piece of material upon another and to provide a presser foot centrally of a pattern of stitching to be formed by the sewing machine, with provision for removing the presser foot and its coordinately movable parts so that the stitching mechanism of the sewing machine may complete the pattern in a single operation.

In the drawings:

Fig. 1 is a plan view of our improved sewing machine with portions of the sewing machine head being broken away to disclose parts therewithin and therebeneath.

Fig. 2 is a front elevation of that portion of our sewing machine directly pertaining to the presser foot and some of its coordinately moving parts, the presser foot being shown in retracted position and a portion of the spring actuator being shown in vertical section.

Fig. 3 is a view similar to Fig. 2 but somewhat enlarged and showing our presser foot in position against the work, portions of the work holder being shown in vertical section.

Fig. 4 is a section on line 4—4 of Fig. 1 and showing means for changing the direction of movement of the work holder.

Fig. 5 is a side elevation of the rear portion of a sewing machine and showing automatic means for stopping the sewing mechanism upon completion of a pattern of stitching upon the work.

Fig. 6 shows the work as it appears with the label thereon and the line of stitching in a "pattern" adjacent the margins of the label and showing by means of arrows the direction taken by the stitching means.

Fig. 7 is a plan of the laterally movable portion of the work holder and a horizontal section exhibiting the control mechanism for all movement of the work holder.

Fig. 8 is a section on line 8—8 of Fig. 4.

Fig. 9 is a section on line 9—9 of Fig. 1 and showing a fragment of stretcher arm 29.

Like parts are identified by the same reference characters throughout the several views.

The principal features of this invention relate to a work holding mechanism, a presser foot mechanism for holding a label upon the work during the greater part of a label sewing operation, a work and label moving mechanism for carrying on a sewing operation, and means for instituting and automatically removing the presser foot without stopping the sewing operation.

The sewing machine in which we incorporate our label sewing devices is a conventional one in which a sewing head 10 is disposed over a bed 11 upon which the direct work holding mechanism is supported. A horizontal arm 12 for the head supports an enclosed crank shaft 13 extending the length of the machine from the head 10 to a driving pulley 14 which is motivated by a belt 15 from any power source (not shown). A needle 16 extending downwardly from the head 10 is constantly reciprocated by the crank shaft 13 when the machine is in operation. The needle end of the machine is the front of the machine for purposes of operation.

The work holder

Beneath the head 10 and supported upon the bed 11, we provide a work holder which is mounted for reciprocation in two directions. For forward and backward movement there is a dovetail slide 17 in guides 18 and upon the slide, we provide a clamp carrier 19 upon which the central portion of the work 20 actually rests as shown in Fig. 3. The clamp carrier is of considerable extent forwardly and backwardly and has marginal guides 21 for a work receiving frame 22 over which the work is laid. This frame is apertured at 23 for reception of a work stretcher 24 supported by a work stretcher arm 29. Around the margins of the aperture in the work receiving frame 22, we provide a clamp ring 27 which is actuated by clamp ring springs 28 and arm 29 which is pivoted at 30 and which is oscillated by a work holder actuator 31. Actuator 31 is connected by means of a link 32 to a pedal (not shown) beneath the bed of the machine and the operator, by pressing on the pedal, can release the work as will now be described.

Assuming that the work holder is empty and the clamp ring and work stretcher are upraised upon the hinge pintle 30, the work may be posi-

5

tioned over the aperture 23. When downward pressure is released on link 32, the clamp ring arm will lower the clamp ring into position upon the work and clamp it between the ring and the work receiving frame 22 through action of coil spring 200 which was compressed by downward pressure of pedal. The action will precede the application of the stretcher 24 because the clamp ring is urged downwardly ahead of the stretcher by clamp ring springs 35. Immediately after the clamp ring bears upon the work, the stretcher 24 forces the central portion of the work downwardly into contact with the clamp carrier 19 because of tension on coil spring 200.

Presser foot

One of the most important features of this invention is the provision of a presser foot to bear centrally upon a label or other article whereby to hold it while stitching operations are accomplished around the margins, and provision for release of the presser foot and shifting to a position to provide unrestricted access to the work during completion of the stitching.

25 Furthermore, our new presser foot is so constructed with reference to the work holder that it moves therewith and when once pressed into position upon a label remains there until its function as a label holding element is completed.

30 It moves with the work and the work holder throughout practically the entire stitching operation. When the stitching is almost complete, the presser foot is released and raises vertically a short distance before swinging out and away from the needle. It then may swing through a complete arc of movement preparatory to the next cycle of stitching operations upon the next label.

35

Figures 1, 2 and 3 illustrate the mechanism which we have devised for presser foot control. The presser foot itself is shown at 40. It is held upon a presser foot arm 41 secured adjustably at 42 to a clamp which is incorporated in a vertically slidable cam tube 43 on a presser foot post 44. On the post is a cam block 45 which coacts with a cam surface 46 of the cam tube 43 when the cam tube is forced downwardly on the post. Thus the presser foot is swung into position upon the work by this cam action as it is lowered. In the lowermost position of the cam tube upon the post 44, the cam block 45 is received in a slot 47 in the tube 43. Thus in the final movement of the tube and, therefore, the final movement of the presser foot into position upon the work, the movement of the parts is

65 The post 44, being rigidly mounted upon the work receiving frame 22, moves therewith and we therefore provide the following mechanism for moving the presser foot into position and for releasing it. The single manual or foot control being operated from a fixed position at 48, we provide a treadle with a link 49 extending upwardly through the bed of the machine to a cross arm 50. This cross arm is rigidly connected to a tubular shank 51 mounted upon an upright post 52 carried by the bed 11 of the machine. Between the bed of the machine and the tubular shank 51, we provide a compression spring 53 which constantly urges the cross arm 50 to its uppermost position which is determined by a collar 54 at the top of the post 52.

The cross arm 50 is hollow and is in telescopic relation to a cross rod 55 which is outstanding from the cam tube 43. Within the cam tube 43 is a spring 56 which bears upon the post 44 and

against the under side of the closed top portion of the cam tube 43. This spring 56 is placed under compression when the presser foot is lowered into position upon the label and remains under compression until the presser foot is to be released from the work, whereupon it returns the presser foot to retracted position.

When the presser foot is in position upon a label and the cam tube is in its lowermost position upon the post 44, latch 58 is urged into engagement with a socket 59 in the cam tube by means of a spring 60 which bears against the under side of the latch release arm 61 and the latch, therefore, holds the presser foot down upon the label even though pressure upon the pedal 48 is removed. When the pressure upon the pedal is released, spring 53 returns the cross arm 58 and the rod 55 to its uppermost position, thus relieving the cam tube for easy return to its uppermost position when the latch 58 is released. 10 15 20

Release of the latch 58 is accomplished by means of a latch release arm 62 provided with a pin 63 to bear upon a cam surface 64 forming part of the arm 61. The latch release arm 62 is rigidly supported upon the bed 11 of the machine and does not move with the work carrying parts. Thus, the pin 63 is not in effective motion transmitting relation to the latch until the work carrier is in a precise predetermined position in relation to the stitching of the label, but when in that precise position, the pin 63 will ride upon the cam surface 64 and withdraw the latch from the socket 59 in the cam tube. When thus released, the cam tube will spring to its uppermost position under the urge of spring 56 and as the presser foot arm 41 is rapidly raised, it is brought in contact with a deflector spring 65 carried by the head 10, and the presser foot and its directly associated parts swing in an arc to a retracted position shown in Fig. 2 where it is in readiness for the next label stitching operation to which it returns upon pressure upon treadle 48. Each time that the label presser foot is released from one label, it travels to a retracted position and then as it is brought again to a label pressing position, it travels through a complete cycle of movement.

Work and label moving mechanism

As stated above, the needle 16 is laterally stationary and carries on its stitching operations merely through vertical reciprocation. The progressive stitching along the margins of a label under the presser foot is accomplished through movement of the work and label holder, which movement is carried on as now to be described. 55

movement is carried on as now to be described. The work holder is moved forwardly and backwardly upon dovetailed slide 17 and it is moved laterally in the marginal guides 21 on clamp carrier 19. Dovetailed slide 17 is connected by means of a pitman 70 to a bell crank 71, one arm of which is slotted at 72 to receive connection with one end of the pitman. The other arm of the bell crank 71 is provided with a cam follower 13 adapted to move in a cam track 74 of a feed wheel 75 provided for step by step rotation. The step by step rotation of the feed wheel 75 is accomplished by a well known type of mechanism including feed dogs 76 which are oscillated by an oscillatory hub 76A connected through arm 77 and link 78 with a rocker 79 which, in turn, is motivated by a connecting rod 80 extending to an eccentric 81 upon the crank shaft 13. Thus, the crank shaft 13 is rotated and the eccentric raises and lowers the connecting rod 80. This connect-

ing rod, as is well known in the art, has its upward terminal vertically bored to receive eccentric rod 81A which constantly reciprocates under the power from the crank shaft 13. Eccentric rod 81A is notched at 82 and a dog arm 83 is provided with a dog 84 to extend through a notch in the wall of the connecting rod and into the notch 82 in the eccentric rod, thus connecting the eccentric rod and the connecting rod. A spring (not shown) urges the dog 84 into engagement with the notch 82 so that normally the eccentric rod 81A and the connecting rod 82 move as one unless special mechanism is provided to break the connection. Thus, when the dog 84 is in engagement 15 in a notch in the rod 81A, the feed wheel 75 is moved in step by step rotation and the bell crank 71 with its pitman 70 are caused to oscillate and reciprocate respectively in control of the dovetailed slide. The work carrier is, therefore, moved 20 forwardly and backwardly to an extent dictated by the precise adjustment of the connection between the pitman 70 and the slotted arm 72 of the bell crank 71.

Lateral movement of the work carrier is accomplished by means of a feed wheel 90 which is rotated in a step by step motion carried on by dogs 91 actuated by rocker 92 and connecting rod 93. Connecting rod 93 is likewise notched at 94 and is connectible to an eccentric rod 95 by 25 means of a dog 96, mounted upon dog arm 97 similar to dog 84 and operating in similar notches. Eccentric rod 95 is vertically reciprocated by connection to cross head 118 which is intermediately pivoted as shown in Fig. 1 and is rapidly oscillated by the same eccentric which operates eccentric rod 81A.

In our new construction, dog arm 83 and dog arm 97 are so connected that either one or the other of said dogs is in engagement and we provide a snap action mechanism whereby alternatively to snap one of the dogs into engagement in its notch or the other dog into engagement in its notch with a quick action.

Each of the feed wheels 75 and 90 is mounted 45 upon its shaft 100 and 101, respectively, said shafts being carried in suitable bearings 102 and 103, respectively, carried by the bed 11 of the machine. At the top of each of said shafts 100 and 101 is a cam head 104 and since the cam 50 heads are identical in construction, we shall proceed to describe one of them with the understanding that the description of the other is unnecessary.

The cam head 104 is plate-like and upon its 55 surface are supported two cam blocks 105 and 106. Midway between the cam heads, a walking beam 107 with roller tipped ends 108 and 109 is mounted for oscillation upon bracket 110. Formed rigidly with the walking beam 107 is an upwardly 60 extending trip arm 111 connected by linkage at 112 with a trip rod 113. Trip rod 113 is relieved at 114 and 115 to receive dog actuator arms 116 and 117, respectively, and at the top of the cross head 118, we provide a spring 119 to bear into 65 either of two notches 120 or 121 as a detent to hold the cross rod 113 in either of two extremes of its motion.

The feed wheels 75 and 90 are so timed that 70 the cam blocks such as 105 and 106 are alternatively brought to bear upon the walking beam terminals 108 and 109. Thus when cam block 106 has tilted the walking beam to the position shown in Fig. 4, the next sequence of motion in the rotation of feed wheel 90 will bring one of 75 the cam blocks on the cam head 104 into posi-

tion against the roller 109 and will tilt the walking beam back to the opposite position in readiness for the next contact of a cam block upon cam head 104. Thus in the cycle of the walking beam movement, the cross rod 113 is thrown from right to left and left to right successively through action of flat spring 201 on lever 202. As it is thrown to the right, dog 84 is thrown into engagement with eccentric rod 81 and the feed wheel 75 is caused to rotate. Then as the 10 cross rod 113 is thrown to the left through walking beam 107, the dog arm 117 is thrown into engagement to complete the connecting rod operation of feed wheel 90 and feed wheel 75 is brought to rest. 15

We have already described the forward and backward movement of the work carrier as carried on through rotation of the feed wheel 75. When feed wheel 90 is rotated, a cam track 125 acts upon a cam follower 126 on the end of a 20 lever 127 pivoted at 128. A slide block 129 is adjustably fixed upon the lever 127 and has an open lug 130 slidably mounted upon a rod 131 carried by an extension 132 of the work receiving frame 22. Lug 130 is in pivotal relation to the slide 25 block 129. The connection between the extension 132 and the work receiving frame 22 is provided by means of screws 133 adjustably receivable through slot 134 in the extension and may be used for purposes of alignment and to assist 30 in the adjustment of the slide block 129 upon the lever 127 when a change in the travel of the work receiving carrier is to be made.

Thus, by means of the control of the feed 35 wheels 75 and 90 and the parts hereinabove described, we have made it possible to move the work laterally and to move it forwardly and backwardly under accurate control thus causing the work to follow a pattern of movement which is dictated by the adjustment of the slide block 129 40 and by the adjustment of the pitman 70 in its connection with the bell crank 71, and because of the step by step movement alternatively of the feed wheels 75 and 90 and the constant operation of the needle 16, the stitching operations following 45 the pattern of movement referred to will marginally stitch a label centrally held by the presser foot.

Starting and stopping operation

While, in general, the starting and stopping of the sewing machine uses conventional parts to which we have not contributed, we shall describe this mechanism so that the interconnection of the various parts and the complete operation of 55 our new label sewing machine may be understood. Fundamentally, the starting and stopping of the machine is accomplished by throwing belt 15 from an idler pulley 140, to the working pulley 141. This is accomplished by means of a pulley 60 arm or lever 142 and a vertical pulley arm rod 143 extending down through the bed 11 of the machine. Rod 143 is notched at 144 so that when the rod is down and the machine is operating, a stop lever 145 is engaged in the notch. 65 This operation is accomplished manually to start the machine. Stop lever 145 is pivoted at 146 and has a cam end 147. Upon the feed wheel 75 is a lug 148 which is so positioned as to come in contact with the cam end 147 when the sewing machine has completed a cycle of operations upon a label. Having come in contact with the cam end 147, stop arm 145 is released from the notch 144 and a compression spring (not shown) attached to the pulley arm or lever actuates such 75

lever to throw the belt onto the idler pulley. The machine is manually started.

We claim:

5. 1. In a sewing machine structure, a work holder to receive, stretch and hold work, and stitching means in position to carry on a stitching operation at a fixed point, connections between the stitching means and the work holder whereby to move the work holder and the work 10 in a predetermined pattern of movement with reference to said stitching means, and a presser foot provided with an arm movable to and from a position to press upon the work within said pattern, means for resiliently pressing said 15 presser foot upon the work, and automatic means for releasing said resilient means and for movement of the arm and said presser foot at a predetermined point in the movement of the stitching means.
20. 2. In a sewing machine, a work holder mounted for lateral and for forward and backward movement, stitching devices for operation upon work in the work holder, separate work holder moving devices for each direction of movement 25 thereof, and connections alternatively connectible between the separate moving devices and the stitching devices whereby to move and change the direction of movement of the work holder so that the entire sewing operation can be completed in a single operation, one of said alternatively connectible connections being provided with adjustable means for changing its range of movement whereby to accommodate various sizes of work.
35. 3. In a device of the character described, a presser foot and mechanism for the support and adjustment thereof for swinging movement of the presser foot to and from a working position, said mechanism including a presser foot supporting arm and a carrier for said arm provided with a supporting element, said carrier and its support having interengageable means whereby in the swinging movement of the presser foot and its supporting arm to arrest the motion of 40 the presser foot and its arm and dispose the presser foot in working position.
45. 4. In a device of the character described for carrying on a working cycle, a presser foot and mechanism for the support and adjustment 50 thereof for movement of the presser foot to and from a working position, said mechanism including a presser foot supporting arm and a carrier for said arm provided with a supporting element, said carrier and its support having interengageable means whereby to arrest the motion of the presser foot and its arm and dispose the presser foot in working position, and a latch for positively positioning the presser foot and for automatic release therefrom for completion of the 55 working cycle.
60. 5. In a device of the character described, a stitching mechanism and power connections for the operation thereof, a work holder to receive and hold work in position to be worked upon by said stitching means, said work holder having separate carriages for movement in a plurality of directions and separate power connections between said first mentioned power connection and said carriages and a control device for alter- 65 natively completing either of said separate power connections whereby to move the work holder in a pattern of movement said separate power connections having adjustable elements to increase or decrease the extent of movement of said work 5 holder in either direction.
6. The combination with a work holder providing a framed opening to expose work in said holder, of a presser foot swingable to and from work holding position upon the exposed work 10 in said frame, a post movable with said work holder and a tubular carrier for the presser foot mounted upon said post, a stop upon the post and a slot in said tubular carrier whereby in the rotation of the presser foot and carrier upon 15 said post to position the presser foot with reference to said frame when the stop is in said slot, and resilient means between the post and the carrier to thrust the carrier to presser foot retracted position.
7. A sewing mechanism including a work holder mounted to transcribe a pattern of movement and provided with an aperture adapted to expose a portion of the work, a post mounted on said work holder and provided with a stop, a 20 tubular member floatably mounted on said post, said member provided with a slot adapted to receive said post stop to limit the floating movement and to position said pressure foot when the stop is in said slot, resilient means intermediate the post and the carrier to normally bias the presser foot toward retracted position, a latch adapted to hold the presser foot in work contacting position during some of said work holder movement, and mechanical means for release of 25 the presser foot during other movement of the work holder.
8. In a device of the character described, a presser foot mounted for movement to and from working position relative to a label stitching 40 means, a support for said presser foot extending across the path of the stitching means while the presser foot is in working position and mechanism for removing the presser foot from such position and actuating it along a uni-directional 45 path of travel to remove its support from the path of the stitching means during the final stitching operation, and means for temporarily arresting such movement of the presser foot and its support pending the final stitching operation 50 and substitution of another label to be stitched.
9. In a label stitching machine, the combination with stitching means adapted to progressively stitch marginal portions of a label to articles to be labeled, a presser foot movable into and out of contact with the label in the space to be enclosed by said stitching line, a support for the presser foot extending across the path defined by the stitching means when the presser foot is in working position, and mechanism for 55 uni-directional actuation of said support adapted to move it out of the path of the stitching mechanism and return it to working position after one stitching operation is completed and in time to initiate a subsequent operation on another 60 label.

RALPH E. MEREDITH.
JOYCE H. MEREDITH.
